UNITED STATES PATENT OFFICE.

FRITZ ALDENDORFF, OF BERLIN-WILMERSDORF, GERMANY; CHARLOTTE ALDENDORFF
WIFE OF SAID FRITZ ALDENDORFF, DECEASED.

AUTOMATIC TELEPHONE SYSTEM.

Application filed January 12, 1925, Serial No. 1,889, and in Germany January 14, 1924.

This invention relates to selectors and telephone systems operating with selectors and its object is to provide devices by which wrong connections arising from the fact that

5 the line finders, group selectors etc. operate too slowly to respond to very quick movements of the switch controllers, are obviated.

In accordance with the invention a selector is used in which there is provided for every

10 line connected to its contact bank a designating contact in addition to the usual test contact, and a brush that wipes over the designating contacts and through which a current flows that passes through an electromagnet

15 which causes the voice current brushes to be stopped on a certain line. The brushes are stopped by a detent that engages with teeth of the brush carrier. In accordance with an-

other feature of the invention the brushes are 20 stopped by an armature (retracting) of an electromagnet and by a member moved with the brushes that has as many teeth or the like as there are individual sets of contacts in the contact bank. The response of the electro-

25 magnet armature is accelerated in accordance with the invention by connecting a condenser in parallel to the electromagnet or weakening the exciting current of the electromagnet after its armature has been attracted, or by 30 causing the armature to retract through the effect of counteracting ampere turns.

A further feature of the invention consists in a selector in which one and the same magnet is used for starting and stopping the selector brushes. The magnet may be arranged

35 to start the selector when it is energized and to stop its operation when the magnet is de-energized. A further feature of the in-

40 vention consists of driving the brushes of a selector by a power such as spring power, and in case they are not stopped on the desired line, in moving them step-by-step by an elec-

45 tromagnet armature until they reach the desired line. The step-by-step motion may be obtained by arranging the electromagnet ar-

50 mature so that it engages with the teeth of the brush carrier and liberates one tooth after another. In accordance with a further feature of the invention the line upon whose

55 contacts in the contact bank of the selector the brushes have been stopped, is marked by changing the potential of a plurality of bank contacts. Further features of the invention consist in using a selector of the aforede-

scribed kind as a line finder, group selector

or connector. The brush carrier may be ar- ranged to execute rotary motions only or it may be arranged to also be moved longitudinally.

The invention is illustrated in the drawing 60 in which

Fig. 1 shows a constructional form of the selector and Fig. 1^a shows a part of a selector whose brush carrier may be moved longitudinally and rotated. 65

Fig. 1^b shows the longitudinal movement controlling mechanism of the switch of Fig. 1^a.

Fig. 2 shows a circuit arrangement for the selector when used as a line finder. 70

Fig. 3 shows circuits of a selector with a longitudinally movable and rotary brush shaft. 75

Fig. 3^a illustrates circuits of a group se- 80

lector whose brushes execute rotary move- 85

ments only.

Fig. 4 shows circuits of a connector that

executes rotary movements only. 90

Fig. 5 shows a circuit in which the quick

stopping effect of the stopping magnet is 95

obtained by inserting a resistance in its ener-

gizing circuit.

Fig. 6 shows a circuit in which the quick- 100

stopping effect of the stopping magnet ar- 105

ature is attained by counteracting ampere

turns.

Fig. 7 illustrates a form of the selector in

which, instead of two toothed wheels as in

Fig. 1 only one toothed wheel is employed. 110

Fig. 8 illustrates diagrammatically a por- 90

tion of the contact bank and shows the dis-

placement of the designating contacts. 95

Selectors whose circuits are arranged as shown in Figs. 2, 3^a and 4 may, on the whole, be built in the manner illustrated in Fig. 1 100

except that a cam disk 300, Fig. 3^a or 400,

Fig. 4 which is not provided in Fig. 1, is

combined with the brush carrier when the

selector is to be used as a group selector or

connector. 105

In Fig. 1, 1 is a shaft which has brushes 2,

3, 4, 5 fixed to it that are insulated from each

other and from the shaft. Also fixed on the

shaft 1 is a toothed wheel 6 whose hub 7 rests

on the bearing 8. Journalled so as to rotate

on the shaft 1 is a toothed wheel 10 with a

spring box 9. The spring box 9 has an up-

wardly extending hub 11 and a downwardly

extending hub 12 that rests on a bushing 13

fixed to the shaft 1. One end of the spring 14 110

of the spring box is connected to the bushing 13 and its other end is attached to the periphery of the spring box 9. When current impulses are sent through the magnet 15 the 5 spring box 9 is rotated in the direction of the arrow 16, a holding pawl (not shown) being provided which prevents backward rotation of the spring box 9. When the spring box 9 is wound up the wheel 17 is held against 10 movement by the pawl 18 of a magnet 19 so that the shaft 1 with the brushes 2, 3, 4, 5 is also prevented from rotating. Mounted on the wheel 17 are two slip rings 20 to which current is conducted by two brushes 21, 22. 15 The two slip rings are interconnected by a contact that is carried round with the wheel 17 when this wheel is moved out of its normal rotary position with respect to the spring box 9. But as soon as the wheel 10 occupies 20 a certain position with respect to the wheel 17 a pin 24 of the wheel 10 raises a pin 23 and thus opens the contact that interconnects the rings 20. This contact or switch is designated 25 in Fig. 2. The spring 14, when it is 25 wound up, tends to turn the brush carrier 1 with its wheel 17 in the direction of the arrow 26 and it executes a turn in this direction when the starting and stopping magnet 19 is energized.

30 In a selector with a longitudinally movable shaft 1', Fig. 1^a, a toothed wheel 17' corresponding to the wheel 17, Fig. 1, and a spring box 9' corresponding to the spring box 9, Fig. 1, and having a circle of teeth 10', is provided. The toothed wheel 17' however has a hollow hub 7' upon which the spring box 9' is adapted to rotate. The shaft 1' extends downwardly through the spring box and has a series of circular teeth 27 with which the 35 pawl of a lifting magnet 28 may engage. The shaft 1' has a groove 29 into which a pin 30 arranged in the box of the wheel 17' protrudes, so that the shaft 1' may move lengthwise in the wheel 17' but cannot turn therein. 40 By the lifting magnet 28 the shaft 1' may be lifted step-by-step and when the wheel 17' is then released by a magnet corresponding to magnet 19, Fig. 1, the shaft is rotated by the spring 14' of the spring box until it is 45 stopped in the manner hereinafter described. The shaft 1' is restored to its normal position by its being turned until a pin 31 of the same strikes against a slide way in the form of a long stop 32. When the shaft is in this 50 position a holding pawl 33, Fig. 1^b, will register with a groove 34 in the shaft so that the latter drops down. When the pin 31 has fallen beneath the slide way 32 the spring turns the shaft a little further round until the 55 pin 31 is restored to the position shown in Fig. 1^a and the holding pawl 201, Fig. 3, engages with the wheel 17' and holds it and the brush carrier in the normal position indicated in Fig. 3.

60 65 By placing Figs. 2, 3 and 4 side by side a

complete circuit arrangement for an exchange with line finders, Fig. 2, group selectors, Fig. 3 and connectors, Fig. 4, is obtained.

It will now be assumed that a subscriber S, Fig. 2, desires to establish a connection 70 with the line 224. When the subscriber S raises his receiver a current flows from the positive pole through the line relay 40, contact 41, sub-station S, contact 42 of the cut-off relay 43 to the negative pole. The line 75 relay 40 closes its contact 44, 45 and opens contacts 46, 47. The opening of the contacts 46, 47 results in the positive pole being disconnected from the designating contacts 48, 49. By the closure of the contact 45 the cut-off relay 43 is connected to the test wire 80 50 and test contact 51 of the calling subscriber. At contact 44 a circuit is closed which extends from the positive pole through the starting relay 51 of the line finder 52. 85 The relay 51 sends a current from the positive pole through its contact 53, brush 54, of the trunk finder, contact 55 of relay 56, starting magnet 19 to the negative pole. The starting magnet 19 pulls its stopping 90 pawl 57 away from the wheel 17 and this latter is now turned at a high speed by the spring 14, Fig. 1. When the wheel 17 with the brushes 58, 59, 60, 61 is moved out of its 95 normal position the off-normal switch 25 is closed and the relay 56 is energized. The starting magnet 19 is then maintained energized by a current that flows through the contact 62 of the relay 64, wiper 58 and the 100 designating bank contacts 65 that are connected to the positive pole of the battery. The magnet 19 remains energized until the brush 58 reaches the bank contact 49. The armature 57 then retracts and stops the wheel 17 so that the wipers 59, 60, 61 are held on 105 the contacts 66, 67, 68. If magnet 19 does not operate fast enough it could happen that the brush 58 oversteps the contact 49 and only stops on the next contact 48 from which the positive pole is also disconnected by the 110 contact 47. In any case, if necessary, as many contacts 48, 49 are disconnected from the positive pole as are necessary to prevent the brush 58 from flying past the last bank contact that is disconnected from the positive 115 pole, which might happen if the armature 57 acts too slowly. The calling line is always the one that corresponds to the last contact 48 that is disconnected from the positive pole. When the brushes are stopped on the first contact 49 disconnected from the positive pole the magnet 19, as soon as its armature 69 falls back, receives a current impulse that flows through contact 69, 70, 71, 63 to the negative pole. The armature 57 is 120 thus again attracted and allows the toothed wheel 17 to turn through an angle corresponding to a further tooth in the direction of the arrow, because, in consequence of the 125 interruption at 69 and of the disconnection 130

of the positive pole from the contact 48, the armature 57 immediately drops back again and again stops the wheel 17. The test brush 58 will now be resting on the bank contact 51 which is connected through the cut-off relay 43 to the negative pole. Hence the relay 72 will be energized by a current flowing from the positive pole through 53, 54, 72, 59, 51, 45, 43 to the negative pole. The self-interrupter 69 is switched off at 70 so that the armature 57 of the magnet 59 remains still. It is to be noted that the magnet 19 is made to allow its armature 57 to drop back extremely quickly by a condenser 73. The relay 72 closes its contact 73 and thus renders the calling line engaged so that further relays like 72 or test relays in the connectors cannot be energized when the brushes of other selectors are stopped on the bank contacts of the calling line. The relay 72 by its contacts 74, 75 also connects the calling line through to the group selector, Fig. 3, so that the impulse relay 202 of the group selector is energized. Furthermore the relay 72 by its contact 76 opens the circuit of the rewinding magnet 15 which would otherwise be closed when the release relay 203 and the relay 64 are energized. The calling subscriber now sends in a series of two impulses, i. e. he causes two interruptions of his loop to take place in rapid succession so that the armatures 204, 205 drop back twice and two impulses flow from the negative pole through contact 206 which was closed (due to a current from the negative pole to 204, 203, 207 to the positive pole) when the relay 202 was first energized, contact 208, contact 209, lifting magnet 28 to the positive pole. The lifting magnet 28 now raises the shaft 1', Fig. 1^a with the brushes 210, 211, 212, 213 step-by-step until they reach the second level of the contact bank. The calling subscriber having now sent in his two hundred impulses, the armatures 204, 205 now remain attracted for a relatively long interval so that the relay 214 which was energized through 206, 214, 215 is kept short-circuited at contact 216 until its armature drops back and the contact 217 is closed. As the vertical off-normal switch 218 was closed at the first vertical step of the shaft the starting magnet 219 now receives a current which flows from the negative pole through 220, 218, 217, off-normal switch 221, 229 to the positive pole. The wheel 17' and the shaft 1' with the brushes 210-213 is now released for rotary movement so that the spring 14' whirls the brushes round until the magnet 219 which is bridged by a condenser 222 and receives current during rotation of the brushes through the contact 223, brush 213 and bank contacts such as 224 connected to the negative pole, is de-energized. This de-energization takes place as soon as the brush 213 reaches a contact 224 whose wire 225 is dis-

connected from the negative pole, this wire leading to a free connector, Fig. 4. The stopping pawl 207 engages with the wheel 17' and arrests the brushes 211, 212, 213 on wires leading to the connector, Fig. 4. In the group selector, Fig. 3 the relay 226 is now energized by a current that flows from the negative pole through 220, retracted armature 227 of the magnet 219, 226, brush 212, wire 228, resistance 401, off-normal contact 402 of the connector to the positive pole. The relay 226 opens the contacts 229, 230, 231 and at the same time extends the voice current wires through the wipers 210, 211 to the impulse relay 402 of the connector. The impulse relay 202 of the group selector is disconnected at contacts 230, 231. This does not however result in the restoration of the group selector because the short circuit around the release relay 203 is kept open at contact 229. The calling subscriber now sends in two tens impulses. On the first retraction of the armature of the impulse relay 402 a current impulse flows from the negative pole through contact 406, 407, 408, wire 409, bank contact 410, wiper 414, contact 415 and through the magnet 419 bridged by the condenser 420. The magnet 419 pulls the holding pawl 418 away from the toothed wheel 417 so that this wheel with the brushes 411-414 is rotated. The brush 414 leaves the contact 410 but is immediately re-connected to negative potential by a long contact 421 so that the magnet 419 remains energized until the brush 410 reaches the contact 422, which in the meantime will have been disconnected from the negative pole by the re-energization of the impulse relay 402. The magnet 419 thus allows the stopping pawl 418 to re-engage with the wheel 417 so as to stop the brushes 411, 414 on the set of bank contacts corresponding to the contact 422. When the second tens impulse affects the relay 402 the brushes 411-414 execute a further long step corresponding to their movement from 410 to 422 so that they now reach the contact 423. It is to be noted that the spring which turns the brushes 411-414 is wound in such a way that the long steps of the brushes keep pace with the numerical impulses from the subscriber. During the interval after the series of ten impulses have been sent in the change over relay 424, which was energized by a current from the negative pole through 406, 422, 425 to the positive pole is de-energized by the short circuit closed at 426 so that the relay 427 is energized by a current that flows from the negative pole through 429, off-normal contact 413, left hand winding of 427 to the positive pole. The impulse wire 431 is connected by the relay 427 and through contact 421 to an interrupter 433 controlled by a cam disk 400, and through this interrupter and a contact 434 it extends to the toothed-

wheel-controlling-magnet 419. When the calling subscriber now sends in his series of unit impulses the magnet 419 is energized at each impulse by a current that flows from the negative pole through 406, 407, 432, 433, 434, 419 to the positive pole. Whenever, during such an impulse, a tooth of the cam disk leaves the interrupter 433, this latter is opened so that the pawl 418 releases the pawl 418 so as to stop the brushes. The off-normal switch 465 keeps the contact 460 closed until the re-winding magnet 415' has completely re-wound the spring box of the selector, at which moment the circuit of the rewinding magnet is opened. When the release relay 403 is de-energized it also opens the contact 466 which results in the de-energization of the relay 226 in the group selector, Fig. 3. If the calling subscriber should not have replaced his receiver, the wipers of the group selector will remain on the trunk leading to the connector, Fig. 4. This can be avoided by an auxiliary relay in the group selector. When the calling subscriber hangs up, the impulse relay 202 drops back and the release relay 203 is de-energized so that the circuit of the magnet 219 is closed at contact 250, this circuit standing from the negative pole through 250, off-normal contact 251, 219, to the positive pole the magnet 219 pulls the pawl 201 out of the toothed wheel 17' and the spring 14', Fig. 1^a, now rotates the brushes and the shaft 1' until the pin 31 strikes the guide way 32 and the holding pawl 33, Fig. 1^b, enters the groove 34 of the shaft. The shaft then drops down until the pin 31 leaves the guide way 32. The spring 14' now turns the shaft a little further around until the off-normal contact 251 is opened and the magnet 219 releases the holding pawl 201 and this latter finally arrests the toothed wheel 17'. In the meantime the spring box is rewound by the rewinding magnet 215' which receives current through the interrupter 261, contact 260, 215', contact 262 of the off-normal switch to the positive pole. When the spring box is rewound the off-normal switch is thrown into its normal position and the circuit of the rewinding magnet 215' is opened at contact 262. By the de-energization of the release relay 203 the restoration of the line finder, Fig. 2, is initiated. When the contact 263 is opened the circuit of the relay 72 is interrupted so that this relay allows its armature to drop back and close the circuit of the restoring magnet 15 at contact 76. The rewinding magnet 15 is energized by a current which flows from the negative pole through the interrupter 80, contact 81, 15, contact 76, contact 83 of the relay 56 to the positive pole or earth. The rewinding magnet 15 now operates until the off-normal contact 51 is interrupted and the relay 56 de-energized. On the de-energization of the relay 56, which only takes place when the spring 14, Fig. 1, 130

wheel-controlling-magnet 419. When the calling subscriber now sends in his series of unit impulses the magnet 419 is energized at each impulse by a current that flows from the negative pole through 406, 407, 432, 433, 434, 419 to the positive pole. Whenever, during such an impulse, a tooth of the cam disk leaves the interrupter 433, this latter is opened so that the pawl 418 releases the pawl 418 so as to stop the brushes. The off-normal switch 465 keeps the contact 460 closed until the re-winding magnet 415' has completely re-wound the spring box of the selector, at which moment the circuit of the rewinding magnet is opened. When the release relay 403 is de-energized it also opens the contact 466 which results in the de-energization of the relay 226 in the group selector, Fig. 3. If the calling subscriber should not have replaced his receiver, the wipers of the group selector will remain on the trunk leading to the connector, Fig. 4. This can be avoided by an auxiliary relay in the group selector. When the calling subscriber hangs up, the impulse relay 202 drops back and the release relay 203 is de-energized so that the circuit of the magnet 219 is closed at contact 250, this circuit standing from the negative pole through 250, off-normal contact 251, 219, to the positive pole the magnet 219 pulls the pawl 201 out of the toothed wheel 17' and the spring 14', Fig. 1^a, now rotates the brushes and the shaft 1' until the pin 31 strikes the guide way 32 and the holding pawl 33, Fig. 1^b, enters the groove 34 of the shaft. The shaft then drops down until the pin 31 leaves the guide way 32. The spring 14' now turns the shaft a little further around until the off-normal contact 251 is opened and the magnet 219 releases the holding pawl 201 and this latter finally arrests the toothed wheel 17'. In the meantime the spring box is rewound by the rewinding magnet 215' which receives current through the interrupter 261, contact 260, 215', contact 262 of the off-normal switch to the positive pole. When the spring box is rewound the off-normal switch is thrown into its normal position and the circuit of the rewinding magnet 215' is opened at contact 262. By the de-energization of the release relay 203 the restoration of the line finder, Fig. 2, is initiated. When the contact 263 is opened the circuit of the relay 72 is interrupted so that this relay allows its armature to drop back and close the circuit of the restoring magnet 15 at contact 76. The rewinding magnet 15 is energized by a current which flows from the negative pole through the interrupter 80, contact 81, 15, contact 76, contact 83 of the relay 56 to the positive pole or earth. The rewinding magnet 15 now operates until the off-normal contact 51 is interrupted and the relay 56 de-energized. On the de-energization of the relay 56, which only takes place when the spring 14, Fig. 1, 130

- is fully re-wound the circuit of the rewinding magnet 15 is opened at contact 83. In cases in which a calling subscriber S replaces his receiver, without the brushes 58, 59, 60, 5 61 having reached his bank contact set, the relay 64 is energized by a current that flows from the positive pole through 85, 86, 87, left winding of 64 to the negative pole. The relay 64 then closes its contact 81 and thus 10 closes the afore-described circuit (negative pole, 81, 15, 76, 83, earth) of the rewinding magnet. The rewinding magnet then operates until the spring box is fully rewound. As soon as a line finder is taken into use 15 the trunk finder 52 is caused to place its wipers 87, 54, 86 onto another trunk; for as long as the brush 87 encounters engaged trunks the stepping magnet 87 receives impulses which flow from the negative pole 20 through the interrupter 89, contact 90, magnet 88, brush 87, contact 83 to the positive pole. The brushes of the trunk finder are thus stepped forward until they reach a trunk whose associated contact 83 is open. 25 In Fig. 7 a manner of arranging the circuits in connection with the designating contacts of the line finder is shown in which the line relay, for example 40' of a calling subscriber also disconnects the battery from two 30 designating contacts 91, 92 as in Fig. 2. The arrangement of Fig. 7 differs from that of Fig. 2 however in that the calling line is connected to the bank contact set of the designating contact 92 that is first reached by 35 the finder wipers and the brushes, if they should overstep the designating contact 92 and only be stopped at the next contact 91, are stepped back by a magnet 93 onto the contact 92. 40 In the arrangement shown in Fig. 5 the stopping magnet 19' is not bridged by a condenser, but its quick operation is brought about by a resistance 94 being included in its energizing circuit as soon as it has attracted its stopping pawl 57'. 45 In Fig. 6 the stopping magnet 19' has two coils. The retraction of the stopping pawl is brought about by the ampere turns of the energizing winding 95 being counteracted by a winding 96 at the moment in which the brush 97 reaches a designated contact. The counteracting ampere turns 96 are stronger to a certain degree than the ampere turns 95 but not so strong as to cause the retracted 55 stopping pawl to be attracted again. 60 In Fig. 3^a a group selector is shown which executes long rotary steps in response to numerical impulses instead of vertical steps. This is accomplished by means of a cam disk 300. The operation of the selector will be obvious from the following description of the operations that take place in setting it onto the desired bank contact group. 65 When a calling party has been connected 66 through to the group selector, Fig. 3^a, its im- pulse relay 301 is energized. It also results in the energization of the release relay 302 (negative pole, 303, 302, resistance 304, positive pole). Assuming that the calling subscriber sends in two numerical impulses so that the armature of the relay 301 drops back twice, a current impulse will flow at each retraction of the armature from the negative pole through 305, 306, 307, 308, ar- 70 resting magnet 319, to the positive pole. The magnet 319 pulls the holding pawl 320 away from the toothed wheel 321 and this wheel with the cam disk 300 and the brushes 322, 323, 324, 325 is rotated by the tensioned spring (similar to 14, Fig. 1). As soon as the 75 pawl 320 is disengaged from the tooth of the wheel 321 and this wheel turns through a fraction of the pitch of the teeth the cam disk 300 closes the contact 326, 327 so that the magnet 319 receives a current that flows 80 from the negative pole through 327, 326, 307, 308, 319 to the negative pole. The magnet 319 now remains energized until the spring 326 drops into the next notch 329 of the disk 300 so as to open the contact 327 and cause the pawl 320 to engage with a tooth of the wheel 321. The brushes 322—325 will 85 now have executed one tens step. The next numerical impulse will now re-energize the magnet 319 in a circuit extending from the negative pole through 305, 306, 307, 308, 319 to the positive pole. The stopping pawl 310 is again withdrawn from the toothed wheel 321, the contacts 326, 327 are again closed until the spring 326 drops into the notch 329 and the holding pawl 320 again engages the wheel 321 and the brushes will then have completed 90 their second long step. 95 In the interval that ensues after the series of numerical impulses the changeover relay 330 is de-energized by its being short-circuited at contact 331 so that the contact 332 is closed and the relay 333 is energized by a current flowing from the positive pole through 332, 333, off-normal contact 334 to the negative pole. The relay 333 by its contact 334 now connects the magnet 319 to the brush 325. If the brush 325 is now standing on the bank contact of a free trunk the magnet 319 remains de-energized and a current flows through the relay 336 in a circuit that extends from the positive pole through 337, 336, 325, wire 338 to the next selector ahead. The relay 336 thus extends the calling party to the next selector. But if the brush 325 is standing on a busy trunk, that is a trunk whose test wire is connected by a contact 339 in the connector to the negative pole, the magnet 319 will be energized by a current flowing from the positive pole through 319, 308, 307, brush 325, contact 339 to the negative pole. The magnet 319 then again withdraws the holding pawl 320 from the wheel 321 and the brushes are rotated by the tension spring until brush 325 reaches a test 100 105 110 115 120 125

or designating contact that is not connected with the negative pole and therefore belongs to a free trunk. The holding pawl 320 now drops into the wheel 321 and arrests the 5 brushes on the contact set of the free trunk.

When the calling subscriber replaces his receiver the contacts 405, 408 are opened and contacts 340, 341 closed. The magnet 319 is now energized by a current flowing through 10 the off-normal contact 334', 341, 319 to the positive pole and this current continues flowing until the cam disk 300 presses the cam 342 against the spring 344' and thus opens the off-normal contact 334'. The holding 15 pawl 320 is then released by the magnet 319 and the toothed wheel 321 with the cam disk 300 and the brushes is then arrested by the holding pawl 320 in the normal position illustrated. The rewinding magnet 345 receives impulses that flow from the negative pole through the interrupter 346, contact 340, 345, contact 347 until the contact 347 is opened by a cam 348 mounted on the spring box. The spring now being fully re-wound the 20 25 rewinding magnet 345 is de-energized.

In Fig. 8 the positions of the bank contacts with respect to each other are diagrammatically illustrated. From this illustration it appears that the designating contacts (as 30 31 48, 49) are displaced with respect to the other contacts of the contact row so that the voice current contacts 51', 51² and the contacts 51 connected to the holding wire are opposite to gaps between the contacts 48, 49. The holding pawl of the stopping magnet is adjusted so that it arrests the toothed wheel (e. g. 17, Fig. 2) moved with the brushes in a position in which the contacting ends of the wipers stand on a gap between two designating contacts but in the middle of the associated bank contacts 51, 51', 51². By this adjustment the greatest time of de-energization of the stopping magnet is attained.

Instead of displacing the bank contacts the 45 same result can of course be obtained by displacing the ends of the brushes with respect to each other in a corresponding manner.

In reference to the selector shown in Fig. 1 it is to be mentioned that instead of the 50 groove 29 and the pin 30 a guide fork 40' placed near the periphery of the wheel 17' and a guide arm 41' projecting from the shaft 1' and arranged to slide in the fork 40' may be provided. By this arrangement the 55 play between the shaft 1' and the wheel 17' can easily be reduced to a fraction of a millimetre.

It is also to be noted that the contact 433 may simply be opened and closed by the 60 stopping pawl 418 instead of using a special cam disk 400 for this purpose. The cam disk 400 could then be dispensed with.

I claim:—

1. In a selector switch, a brush, bank contacts, a self-contained power device for driv-

ing said brush to any desired bank contact and then to a normal position, a brush-arresting member that moves with said brush, an electromagnet whose armature stops the brush on its deenergizing, and a circuit 70 through said bank contacts for the electromagnet which is opened when the brush reaches a desired bank contact.

2. An electrically operated switch comprising bank contacts, a brush, a self-contained power device that rotates the brush always in the same direction, a toothed brush-arresting member that travels with the brush, an electromagnetically operated stopping member adapted to engage with the teeth of 75 said arresting member to stop the brush on any individual bank contact, electric circuits local to the switch which include bank contacts of same for controlling said stopping member, and a line loop for controlling said 80 local circuits.

3. An electrically operated switch comprising bank contacts, a brush, a spring that rotates the brush always in the same direction, a toothed brush-arresting member that travels with the brush, an electromagnetically operated stopping member adapted to engage with the teeth of 90 said arresting member to stop the brush on any individual bank contact, electric circuits local to the switch for 95 controlling said stopping member, and a line loop for controlling said local circuits.

4. In a selector switch, a brush, bank contacts, a spring for driving said brush to any desired bank contact and then to a normal position, a brush-arresting member that moves with said brush, and an electromagnet whose armature stops the brush on its de-energization. 100

5. In a switch, bank contacts, a toothed wheel, brushes that wipe over said contacts, a self-contained power device for moving the brushes and toothed wheel always in the same direction, a stopping pawl normally in engagement with said toothed wheel, an electromagnet for lifting said pawl from the toothed wheel to start the motion of the brushes and for letting the pawl engage with the wheel to stop the brushes on any desired individual set of bank contacts, and a condenser which influences said electromagnet to quicken the action of its armature. 105 110 115

6. In combination with a link circuit or trunk, bank contacts, brushes that wipe over the bank contacts, a brush carrier, a toothed member on the brush carrier, a brush-stopping member, an electromagnet for operating the brush-stopping member, a power device for driving said brush carrier in a continuous motion until the brushes reach a desired set 120 of bank contacts, a starting circuit for starting the motion of the brushes, a motion-maintaining circuit including said electromagnet, one of said brushes and bank contacts over 125 which it travels, a trunk connecting relay for 130

- connecting two of said brushes to the trunk, and a circuit for energizing said relay that extends through one of said brushes and a bank contact of the switch.
- 6 7. In a switch, bank contacts, means for varying the condition of the bank contacts, brushes that wipe over the bank contacts, means for propelling the brushes, a test magnet for testing the condition of the bank contacts and stopping the action of the propelling means when the brushes reach bank contacts that are in a certain condition, and a condenser cooperating with the test magnet for accelerating its stopping function.
- 15 8. In a switch, rows of sets of bank contacts, brushes for selecting any said row, a self-contained power device for driving a set of brushes in a continuous motion over a plurality of selectable rows of sets of bank contacts, a toothed member that moves with said brushes, and a stopping member that engages with the toothed member and stops the brushes when they reach a desired individual set of bank contacts.
- 25 9. In a switch, rows of sets of bank contacts, a longitudinally movable brush shaft with brushes adapted to cooperate with the bank contacts, a magnet for setting the brush shaft into a position in which its brushes are in line with a said row of sets of bank contacts, a self-contained power device for moving the brush carrier so that its brushes travel in a continuous motion over the row onto which they have been set, an arresting member that moves with the brushes when they execute continuous motion, and a stopping member that engages with the arresting member and arrests it and the brushes when they have reached any desired set of bank contacts.
- 35 10. In a selector switch, rows of sets of bank contacts, brushes for selecting any said row, a self-contained power device for driving said brushes to any desired set of contacts in a row and then to a normal position, a brush-arresting member that moves with said brush, an electromagnet whose armature stops the brush on its deenergization, and field-affecting means for affecting the field of said electromagnet to quicken the brush-stopping action of its armature.
- 45 11. An electrically operated conversational switch comprising, rows of sets of bank contacts, brushes for selecting any said row, a self-contained power device for rotating said brushes over a selected row of bank contacts, a toothed brush-arresting member that rotates with the brushes, an electromagnetically operated stopping member adapted to engage with the teeth of said arresting member to stop the brushes on any individual set of bank contacts, electric circuits local to the switch for controlling said stopping member, and a line for controlling said local circuits.
- 55 12. An electrically operated switch comprising, rows of sets of bank contacts, brushes for selecting any said row, a self-contained power device for driving said brushes in a continuous motion over a plurality of selectable rows of sets of bank contacts, a toothed brush-arresting member that rotates with the brushes, an electromagnetically operated stopping member adapted to engage with the teeth of said arresting member to stop the brushes on any individual set of bank contacts, electric circuits local to the switch for controlling said stopping member, and a line for controlling said local circuits.
- 65 13. In a switch, rows of sets of bank contacts, brushes, a longitudinally movable brush-carrying shaft, a magnet for moving the shaft step-by-step longitudinally until its brushes are in line with the said row, and a self-contained power device for rotating the shaft continuously until its brushes reach a desired set of bank contacts.
- 75 14. In a selector, sets of bank contacts, brushes, a power device for driving the brushes over said contacts, means for stopping the brushes on a desired set of contacts, and a magnet for moving the brushes onto the desired set of contacts if the stopping means fails to act.
- 85 15. In a selector, sets of bank contacts, brushes, a power device for driving the brushes over said contacts, a toothed member that moves with said brushes, a stopping pawl that engages with said member to stop the brushes on a desired set of bank contacts, and a magnet with an armature that cooperates with the toothed member to move the brushes onto the desired set of contacts if the stopping pawl fails to act.
- 95 16. A selector comprising horizontal curved rows of bank contact sets, brushes, a longitudinally movable and rotatable brush carrier, a stepping mechanism for stepping the brush carrier upwards until its brushes reach a desired row of bank contact sets, a power device for then whirling the brush carrier round until its brushes reach a desired bank contact set, and an electromagnetically operated stopping member which engages with the brush carrier to stop the brushes on said bank contact set.
- 105 17. In a power driven hunting switch, bank contacts, brushes that hunt for a desired set of said contacts, a test magnet for controlling the movement of said brushes, and means operative during the hunting action of said brushes for accelerating the controlling function of the test relay.
- 110 18. A switch comprising, bank contacts, brushes that wipe over the bank contacts, a brush carrier, a spring for driving the brushes, a toothed member attached to the brush carrier, a stopping pawl that engages with the toothed member to stop the brushes on a desired set of bank contacts, an electromagnet for controlling the stopping pawl, a circuit for energizing the electromagnet to withdraw

the stopping pawl from the toothed member and to enable the spring to move the brushes, and a second circuit for maintaining the electromagnet energized until the brushes have 5 reached a desired bank contact, said second circuit including one of said brushes and some of said bank contacts.

19. A switch comprising, bank contacts, brushes that wipe over the bank contacts, a 10 brush carrier, a spring for driving the brushes, a toothed member attached to the brush carrier, a stopping pawl that engages with the toothed member to stop the brushes on a desired set of bank contacts, an electromagnet for controlling the stopping pawl, a 15 circuit for energizing the electromagnet to withdraw the stopping pawl from the toothed member and to enable the spring to move the brushes, a second circuit for maintaining the electromagnet energized until the brushes 20 have reached a desired bank contact, said second circuit including one of said brushes and some of said bank contacts, and means for retensioning said spring.

23. 20. A switch comprising, bank contacts, brushes that wipe over the bank contacts, a brush carrier, a self-contained power device for driving the brushes, a toothed member attached to the brush carrier, a stopping pawl 25 that engages with the toothed member to stop the brushes on a desired set of bank contacts, an electromagnet for controlling the stopping pawl, a circuit for energizing the electromagnet to withdraw the stopping pawl from the 30 toothed member and to enable the power device to move the brushes, a second circuit for maintaining the electromagnet energized until the brushes have reached a desired bank contact, said second circuit including one of said 35 brushes and some of said bank contacts, and a condenser for affecting the field of said electromagnet to quicken the stopping action of said pawl.

21. In a power-driven selector, an impulse 40 receiving relay for receiving electrical im-

pulses, brushes, bank contacts, and a magnet for first causing the power to move the brushes step-by-step in response to impulses received by said relay until a desired group of bank contacts is reached and for then causing the 50 power to move the brushes continuously until a desired bank contact set is reached.

22. The combination of a switch comprising bank contacts, brushes, a brush carrier, a toothed wheel adapted to rotate with said brush carrier, a power device for rotating said brush carrier, a brush-positioning pawl that cooperates with said wheel, lines, electric impulse producers for transmitting impulses over said lines, and an electromagnet for operating said pawl relatively to said wheel to permit said power device to move said brushes stepwise in the rhythm of impulses sent from said impulse producer over said lines. 55

23. The combination of a switch comprising bank contacts, brushes, a brush carrier, a toothed wheel adapted to rotate with said brush carrier, a power device for rotating said brush carrier, a brush-positioning pawl that cooperates with said wheel, lines, electric impulse producers for transmitting impulses over said lines, an electromagnet for operating said pawl relatively to said wheel to permit said power device to move said brushes 70 stepwise in the rhythm of impulses sent from said impulse producer over said lines, and an electromagnet for lifting said pawl from said wheel. 75

24. A rotary switch comprising bank contacts, brushes, a brush carrier, a toothed wheel fixed on the brush carrier, a pawl normally engaging with the toothed wheel, a power device for driving the brush carrier, and a single magnet for operating said pawl to allow 80 the power device to move the brushes in steps of different lengths.

In testimony whereof I have affixed my signature.

FRITZ ALDENDORFF.
